FOREIGN PATENT DOCUMENTS

WO 0229284 4/2002

Primary Examiner — Patricia Palasik

(74) Attorney, Agent, or Firm — Dykema Gossett PLLC

(57) **CLAIM**

The ornamental design for a linear actuator accessory, as shown and described.

DESCRIPTION

FIG. 1 is a perspective top view of my new and ornamental design for a linear actuator accessory control box.

FIG. 2 is a perspective bottom view thereof,

FIG. 3 is a perspective top view identical to FIG. 1 but with its cover in an opened state,

FIG. 4 is a top plan view thereof,

FIG. 5 is an elevational left side view thereof,

FIG. 6 is an elevational right side view thereof,

FIG. 7 is a bottom plan view thereof,

FIG. 8 is an elevational front view thereof; and,

FIG. 9 is an elevational rear view thereof.

1 Claim, 3 Drawing Sheets(56)
